DESIGN FOR A TEXTILE FABRIC

Ira Strauss, Woodmere, N. Y.

Application December 1, 1933, Serial No. 49,915

Term of patent 14 years

To all whom it may concern:

Be it known that I, IRA STRAUSS, a citizen of the United States of America, and resident of Woodmere, Long Island, county of Nassau, State of New York, have invented a new, original, and ornamental Design for a Textile Fabric, of which the following is a specification, reference being had to the accompanying drawing, forming a part thereof.

I claim:

The ornamental design for a textile fabric, as shown and described.

IRAH STRAUSS.
